(57)

CLAIM

The ornamental design for a fitting for lashing and blocking a load, as shown and described.

DESCRIPTION

FIG. 1. Is an isometric front view from above of a fitting for lashing and blocking a load;

FIG. 2 is an isometric back view from above of the invention;

FIG. 3 is an isometric front view from below of the invention; and,

FIG. 4 is an isometric back view from below of the invention.

1 Claim, 1 Drawing Sheet
